UNITED STATES PATENT OFFICE

ZOE S. OSBORN, OF COLORADO SPRINGS, COLORADO

STORE FRONT

Application filed October 4, 1928. Serial No. 310,347.

This invention relates to stores, and has for one of its objects to provide a novel, simple and inexpensive front for buildings of this character which shall be so constructed and arranged as to display candy, popcorn and similar articles in the most attractive manner and which shall permit the articles on display and articles within the store to be sold without necessitating purchasers entering the store.

A further object of the invention is to provide a store front of the character stated which shall be so arranged as to permit persons approaching the store from one direction to obtain a direct and clear view of the articles on display and so as to permit persons approaching the store from the opposite direction to obtain a reflected and clear view of the articles.

20 A further object of the invention is to provide a store front of the character stated wherein its arrangement shall be such as to prevent purchasers standing in front of the store from interfering with or being annoyed by persons passing the store.

With the foregoing and other objects in view, the nature of which will appear as the description proceeds, the invention consists in the construction, combination and arrangement of parts hereinafter fully described, claimed and illustrated in the accompanying drawings, wherein:

Figure 1 is a view in front elevation of a store equipped with a front constructed in accordance with my invention,

Figure 2 is a sectional view taken on the horizontal plane indicated by the line 2—2 of Figure 1,

Figure 3 is a sectional view taken on the vertical plane indicated by the line 3—3 of Figure 2,

Figure 4 is a sectional view taken on the vertical plane indicated by the line 4—4 of Figure 1,

Figure 5 is a sectional view taken on the vertical plane indicated by the line 5—5 of Figure 4,

Figure 6 is a perspective view of a fragmentary portion of the store front, and

Figure 7 is a sectional view taken on the

plane indicated by the line 7—7 of Figure 6. Referring in detail to the drawings, in the several views of which corresponding parts are designated by like reference characters, A generally indicates the store and B the novel front thereof. The store A which may be of any well-known or appropriate construction, is shown as embodying side walls 5 and 6 and a roof 7.

The arrangement and construction of the store front B constitutes the subject matter of the present invention, and such front comprises a panel 10 which is preferably opaque, a counter 11, and a window 12. The counter 11 extends inwardly from the upper edge of the panel 10 and is covered with sheet metal, as shown at 13. The counter 11 is adapted to receive the goods to be displayed, and the goods are protected from dust and other foreign matter and are guarded against being handled by prospective purchasers by vertical and horizontal panels 14 and 15 which may be made from glass or any other suitable transparent material. The panels 14 are arranged upon the counter 11 at the front edge of the latter, and the panel 15 which is narrower than the counter 11 extends rearwardly from the upper edge of the panel 14. A narrow panel 16 which may be made from glass or any other suitable material, extends upwardly from the rear edge of the counter 11. The counter 11 and the panels 14, 15, and 16 constitute in effect a show case having the greater portions of its rear and top sides open, and the panels 14 and 15 are supported from 80 and secured to the counter by brackets 17.

The window 12 which may be of any well-known or appropriate construction, is slidably mounted in vertical guides 18, and is adapted to be supported in raised position by counterweights 19 which are connected to the window by chains 19^a. The counterweights are arranged in the guides 18, and the chains 19^a pass over pulleys 20 journaled in the guides. The window 12 contacts with the upper side of the panel 15 when in closed position, and is located at a considerable distance above this panel when in fully opened position. The counter 11, panels 10, 14, 15 and 16 and window 12 are of the same width, 100

and are arranged at an angle with respect to the sidewalk so as to permit persons approaching the store from one direction to obtain a direct and clear view of the goods on display. These parts extend at an obtuse angle rearwardly from the side wall 6 to the door 21 of the store. The door 21 extends from the inner ends of these parts to the other side wall 5 of the store, and secured against said wall is a mirror 22 which extends to the sidewalk. The panels 10 and 14, the counter 11 and window 12 are arranged at an angle of about twenty-five degrees to the sidewalk, and the mirror 22 is arranged at right angles to the sidewalk. The mirror permits persons approaching the store from the opposite direction to obtain a clear view of the goods on display. The roof 7 overhangs the panels 10 and 14, counter 11, window 12, door 21 and mirror 22, and provides in conjunction with these parts a vestibule or space 23 extending rearwardly from the sidewalk and which is provided for the accommodation of prospective purchasers and purchasers being waited upon. The ceiling 24 is provided with an opening 25 for the reception of the window 12 when the latter is in raised position. Suitable window lights 26 arranged in advance of the window 12, extend downwardly from the ceiling 24 to a plane below the upper edge of the window 12 when the latter is in closed position. A panel 27 arranged below the counter 11 in rear of the panel 10, provides in conjunction with the counter 11 and panel 10 an enclosed storage space and is equipped with doors 28. The ends of the show case are closed by panels 29.

From the foregoing description, taken in connection with the accompanying drawings, it will be apparent that the store front comprises a counter and mirror so angularly related to each other and to the sidewalk that the goods on display will be in full view of persons approaching the store from opposite sides thereof, that the angular arrangement of these parts provides a vestibule in which customers may be served without interference from persons passing the store, and that the store front is attractive in appearance. It will also be apparent, that the obtuse angular arrangement of the counter permits it to be made of considerable length as compared to the width of the store, and the connection between the window 12 and the panel 15, when the former is closed, provides for the protection of the goods after hours and during inclement weather.

Changes in details may be made without departing from the spirit or scope of the invention as claimed.

What I claim as new is:

In a store, a display front embodying a counter, a transparent panel extending upwardly from the front edge of the counter, a

transparent panel extending rearwardly from the upper edge of said first panel, a vertically adjustable window arranged above the counter and adapted to contact with the upper side of said second panel when in closed position, and a panel arranged below the counter.

In testimony whereof I affix my signature.
ZOE S. OSBORN.
